(57) **CLAIM**

The ornamental design for an inflatable fall recovery mobility assist device, as shown and described.

DESCRIPTION

FIG. 1 is a perspective view of an inflatable fall recovery mobility assist device showing my new design;

FIG. 2 is a side elevational view thereof; the opposite side being a mirror image thereof;

FIG. 3 is a front elevational view thereof;

FIG. 4 is a back elevational view thereof;

FIG. 5 is a top elevational view thereof; and,

FIG. 6 is a bottom elevational view thereof.
